(57) **CLAIM**

The ornamental design for a sleep comforter, as shown and described.

DESCRIPTION

FIG. 1 is a front left perspective view of a sleep comforter, showing my new design;

FIG. 2 is a front elevational view thereof;

FIG. 3 is a rear elevational view;

FIG. 4 is a right elevational view thereof;

FIG. 5 is a left elevational view thereof;

FIG. 6 is a top plan view thereof; and,

FIG. 7 is a bottom plan view thereof.

The broken lines surrounding the openings (the flaps in the sleep comforter) indicate stitching and are part of the claimed design.
